(57) **CLAIM**

I claim the ornamental design for a computer table, as shown
and described.

DESCRIPTION

The file of this patent contains at least one drawing (photograph) executed in color. Copies of this patent with color drawings (photographs) will be provided by the Patent and Trademark Office upon request and payment of the necessary fee.

FIG. 1 is a left side elevation of a computer table showing
my new design.

FIG. 2 is a right side elevation thereof.

FIG. 3 is a rear view thereof.

FIG. 4 is a front view thereof.

FIG. 5 is a rear view with cabinet open thereof.

FIG. 6 is a top view thereof.

FIG. 7 is a bottom view thereof; and,

FIG. 8 is a rear perspective view showing the inside shelf
thereof.

The surfaces or portions of the article not shown in the
drawing or described in the specification form no part of the
claimed design.
